UNITED STATES PATENT OFFICE.

LEWIS FRITZ, OF CHICAGO, ILLINOIS.

BRUSH.

Application filed June 17, 1922. Serial No. 569,001.

To all whom it may concern:

Be it known that I, LEWIS FRITZ, a citizen of the United States, and a resident of the city of Chicago, county of Cook, and State of Illinois, have invented certain new and useful Improvements in Brushes, of which the following is a specification.

My invention relates to new and useful improvements in brushes particularly to the class of shaving brushes wherein provision is made for introducing a soap compound within the brush from a reservoir or supply in the handle, and has for its principal object the provision of an improved construction of this character which will be highly efficient in use.

A further object of the invention is the provision of a brush of this character for introducing a soap compound within the brush from a reservoir in the handle which is capable of holding the soap compound in a pasty or like form.

A further contemplation of the invention is the provision for controlling the supply of soap compound introduced to the brush whether in a pasty or liquid form, preventing leakage of the soap compound from the reservoir when the brush is not in use.

Other objects will appear hereinafter. The invention consists in the combinations and arrangements of parts hereinafter described and claimed.

The invention will be best understood by reference to the accompanying drawings forming a part of this specification, and in which,

Figs. 1 and 2 are side elevational views of a brush embodying the invention.

Fig. 3 is a vertical sectional detail view of the same taken substantially on line 3—3 of Fig. 1,

Fig. 4, is a horizontal sectional detail view of the same taken substantially on line 5—5 of Fig. 1.

Fig. 5 is a sectional view showing the valve construction.

In carrying my objects into effect, I provide a reservoir (a) within the handle B of the brush part C. The reservoir consists of parts 10 and 11, cylindrical in shape, the part 10 being provided with internal screw threads 12, as shown, which co-operate with external screw threads 13 formed on the part 11 affording means for adjusting the parts 10 and 11 longitudinally with respect to each other. The part 11 is provided with

an integral depending tube 14, which extends through an opening 15 formed in a block 16 of cylindrical shape, and which is formed of rubber carrying the bristles 17 of the brush. The bottom wall 18 of the lower part 11 of the brush is slightly tapered radially toward the tube 14, the purpose being such that the tapered walls will serve as a guide for guiding soap compound from the reservoir (a), when passing into the tube 14.

As clearly shown in Figs. 3 and 4, the bristle block 16, in this instance, comprises parts 19 and 20 hingedly connected together as at 21 by semi-circular ring members or bands 22 and 23 which are locked together so as to tightly embrace the tube 14 by an eccentric lock 24 of any approved type.

By inspecting Fig. 3 of the drawings it will be noted that the upper portions of the bristle block parts 19 and 20 surround the lower portion of the handle part 11 slightly above the point where the bottom wall 18 tapers inwardly, as indicated at 25. The purpose of this and the principal object of forming the bristle block into parts is to prevent warping or expanding of the material forming the parts 19 and 20 which would cause the bristles 17 to become loose and disengaged from the block parts. This warping or expansion of the block parts 19 and 20 is prevented by the semi-circular ring members 22 and 23 which are fixed to the block parts by suitable screws 25 and which are locked together by the eccentric lock 24.

In introducing the soap compound, which may be in its pasty or liquid form, through the tube 14 from the reservoir (a), the handle part 10 is turned so as to move toward the part 11, this movement being accomplished through the medium of the screw threads 11 and 12, and during such movement the soap compound will be forced through the tube 14 to the bristles 17. In addition to the part 10, which is employed for the purpose of introducing the soap into the bristles 17, I also provide a cylindrical plunger 26, which, in this instance, is in the form of a disc arranged in the part 10 and adapted to rest on the soap compound contained within the reservoir. Surrounding the peripheral edge of the plunger 26 is a suitable insulating material 27, which, in this instance, is preferably formed of rubber and which frictionally engages the interior side walls of the part 10 to prevent leakage of the soap compound from

the reservoir. In order to manipulate the plunger 26, I provide a central opening 28 in the top wall of the part 10 for the passage of the finger of the user. It is to be especially noted that by the employment of the flat plunger 26 practically every bit of the soap compound will be discharged from the reservoir leaving very little, if any at all, to corrode the interior of the same.

As already stated herein, my improved shaving brush is adapted to hold a soap compound within the reservoir (a) formed in the handle B either in pasty or liquid form as it becomes necessary that means be provided to prevent the flow of the soap compound through the tube 14 when the brush is not in use. In this connection and to accomplish this object I form on the adjacent inner sides 30 and 31 of the block parts 19 and 20 recesses 32 and 33 into which a valve pin 34 is mounted to slide, said valve pin being provided with an opening 35 which is adapted, when in the proper position, as shown in Fig. 5, to register with the passage 36 of the tube 14. One end of the valve pin 34 is provided with a flanged head 37 which is adapted to engage recesses 38 and 38' formed in the parts 19 and 20, the purpose of which being to predetermine when the opening 35 is in registration with the passage 36 and to prevent the valve pin 34 from being pushed or forced beyond the passage 36.

I also provide means for locking the valve pin 34 either in its operative or inoperative position, this means comprises a buckled spring leaf 39 seated in a recess 40 formed in the bristle block part 19 and fixed thereto by a suitable screw 20'. The buckled end 41 of the spring 39 is adapted to alternately engage screws 42 and 43 according to the position of the valve pin 34.

It is known that there are on the market at the present time a variety of shaving brushes of this class but none of them are provided with a reservoir which is capable of containing a soap compound either in its

liquid or pasty form and it is this feature together with my selective means for introducing the soap compound to the bristles of the brush and my selective means of controlling the passage of the soap compound into the bristles, that I claim to be of a great commercial value and utility over the present constructions.

The operation of my improved brush, when in practice, is obvious from the description herein set forth and by inspection of the drawings and it need be only mentioned here that the simplicity of the construction is of a great advantage over the present constructions of a brush of this character and can be manufactured at a small cost and of any required size.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having described my invention, what I claim as new and desire to secure by Letters Patent is:

A shaving brush including a handle providing a reservoir and having an outlet tube extending at one end, a brush head including brush parts surrounding a portion of the outlet tube, means providing a hinged connection between said parts, said means including semicircular members hinged together and fixed to the brush parts, and locking means for the free ends of said semicircular members including an eccentrically mounted locking lever.

In testimony whereof I have signed my name to this specification in the presence of two subscribing witnesses.

LEWIS FRITZ.
